UNITED STATES PATENT OFFICE.

FRANK DAVIS JACOBS, OF NORTHAMPTON, MASSACHUSETTS, ASSIGNOR
TO PROTECTED METAL COMPANY, OF SPRINGFIELD, MASSACHUSETTS,
A CORPORATION.

MACHINE FOR MAKING ROOFING MATERIAL.

No. 816,661.

Specification of Letters Patent.

Patented April 3, 1906.

Application filed August 1, 1905. Serial No. 272,266.

To all whom it may concern:

Be it known that I, FRANK DAVIS JACOBS, a citizen of the United States of America, residing at Northampton, in the county of 5 Hampshire and State of Massachusetts, have invented new and useful Improvements in Machines for Making Roofing Material, of which the following is a specification.

This invention relates to improvements in machines for coating a strip of material fed therethrough with strips of another material applied on both sides thereof, and it has special reference to a machine for thus coating a strip of sheet metal in the manufacture 15 of roofing and like material, such as that which forms the subject-matter of Letters Patent of the United States issued to me on April 25, 1905, and numbered 788,358, the object of the invention being to provide a 20 machine whereby a strip of metal or like material may have applied to both sides thereof, which have previously been treated with a suitable adhesive, another strip of coating material, means being provided to cut this 25 strip into predetermined lengths automatically.

The invention is fully illustrated in the accompanying drawings, in which—

Figure 1 is a plan view of the machine, 30 showing a strip of material therein. Fig. 2 is a side elevation of that side of the machine shown at the top of the sheet in Fig. 1. Fig. 3 is a side elevation of the opposite side of the machine to that shown in Fig. 2. Fig. 4 is 35 an end elevation of the right-hand end of the machine, as shown in Fig. 1, and shows particularly the means for shearing off the lengths of the coating material from the strip. Fig. 5 is a side elevation of the gears 40 whereby the pressing-rolls and feed-rolls are rotated intermittently. Fig. 6 is a sectional elevation on line 6-6, Fig. 1, and shows the gears which operate the shearing devices. Fig. 7 is a side elevation of the gears which 45 actuate the shearing devices, showing their inactive position during the time when the strip to be cut is being coated.

Referring now to the drawings, *a* indicates the legs or standards on which a trough-like 50 bed *b* is supported. Preferably this trough is cast with suitable sockets *c* on the under side thereof, into which the legs *a* enter and

are secured. The trough-like bed *b* is closed at both ends, and mounted at each end thereof is a pair of feed-rolls, (indicated by *d* at one end and by *f g* at the other.) Of these two pairs of feed-rolls the lower-rolls *e* and *f* rotate in fixed bearings, while the upper rolls *d* and *g* are movable relative to the lower rolls and are held in contact with the latter by 60 means of a weighted arm *h*, pivoted at *j* near each end of these rolls and bearing against the boxes in which the shafts of these rolls are seated. In this way a constant pressure may be applied to material passing through 65 these feed-rolls, which material is indicated by *m*.

As shown in the side elevations Fig. 2 and 3, the strip of material *m* passes under an idler-roll *o*, located transversely of the bed about midway between its ends. This trough-like bed contains the adhesive solution into which and through which the strip of material is fed by means of the rolls *d e* and *g f*, heretofore described, the strip being 75 immersed in the solution during its passage through the trough. The nature of this adhesive when used to manufacture roofing material after the manner described in my said prior United States Letters Patent renders it necessary to apply it to the strip of material in the presence of heat, and therefore beneath the trough-like bed *b* a number of burners *p* are located, preferably for the use of liquid or gaseous fuel, whereby the 80 proper temperature may be maintained in the adhesive substance in the trough. As the rollers *g* and *f* are located just beyond the end of the bed *b*, the material *m* as it passes therethrough will carry more or less of the 85 adhesive substance with which it is coated, and it is the function of these rolls, acting as wiper-rolls, to clear the surface of said strip of material of all of the latter but the quantity required to effect the adhesion of the 90 coating strip to be applied thereto, and therefore beneath these rolls a drip-pan or receptacle *q* is provided (see Fig. 3) into which such material as is wiped off the strip by the 95 action of the rolls may fall, some of it, of course, flowing back on the top of the strip into the trough. To prevent the hardening of this adhesive on the rolls, the latter are made hollow, and through a suitable pipe *r*

100

steam is introduced through the shafts of the rolls to maintain as high a temperature in the latter as may be necessary to keep the adhesive substance in a fluid state.

- 5 During the passage of the material *m* through the bed and after it emerges from the latter and passes through the various rolls to the point at which it is sheared off into lengths its opposite edges run between 10 guide-strips *s*, (shown in dotted lines in the side elevations, Figs. 2 and 3, and in plan in Fig. 1,) these guide-strips extending from the rolls *d e* to beneath the idler-roll *o* and from thence to the rolls *g f*, from which point they 15 extend on to the shearing-point, as shown. A portion of these guide-strips as they approach the shearing-point is shown in Fig. 6. At the right-hand end of the machine, as shown in the general views, Figs. 1 and 3, 20 two rolls *t* and *v* of coating material are supported one above and the other below the line of movement of the sheet-metal strip through the machine, a strip of coating material from the roll *t* being carried down around 25 a presser-roll *w* and another strip from the roll *v* being carried around a like roll *x*, between which rolls the material *m* passes, these serving to press the coating material firmly against the opposite sides of the strip 30 *m*. Like the feed-rolls heretofore described, these presser-rolls are constructed in such manner that the upper one *w* may be moved vertically toward and from the lower, it being held in contact with the latter at a predetermined pressure by means of a weight 35 on an arm *4*, which has the same function as the weighted arm *h* on the feed-rolls *d* and *g*.

At the extreme end of the machine a driving-shaft 5 is located transversely of the end 40 thereof, and on this shaft, side by side, are two broken gears, the inner one, as shown in Figs. 1 and 4 and indicated by 6, serving to drive the roll *x* through the pinion 7, fixed on the end of the shaft of said roll. Referring 45 to Fig. 5, it will be seen that the teeth on this gear 6 extend about three-quarters of the distance around it, and when the teeth on this gear run off the pinion 7 the edge of a ring 8 will come to a bearing against the flattened 50 surface 9 of a ring 10, secured to the side of the pinion 7, thereby locking the presser-roll *x* against rotation until the inactive part of the gear 6 has been rotated past the pinion 7, whereupon the teeth of the gear again 55 mesh with those of the pinion to continue the rotation of the latter. It is thus clear that by means of the proportion of the toothed part of the gear 6 to the number of teeth in the pinion 7 the presser-rolls may be made to 60 deliver any length of material *m* and then come to a stop for a predetermined period, which period will be measured by the length of the dead space on the gear 6. The presser-rolls *w* and *x* at one end are provided with 65 gears 14 and 15, which intermesh to rotate

them together, and on the roll *x* outside of the gear 15 is a beveled gear 16 (see Figs. 1 and 2) in mesh with the beveled pinion 17 on a short shaft 18, which in turn, by means of a beveled pinion 19, meshing with a similar one 20 on the end of the shaft 21 of the feed-roll *f*, drives this latter roll, and by means of gear connections similar to the presser-rolls the roll *f* will rotate the roll *g* above it. The rolls *d* and *e* at the opposite end of the machine are similarly equipped with intermeshing gears to rotate together and are positively driven in unison with the rolls *f* and *g* by means of a shaft 22, running alongside of the bed *b* and having beveled pinions 23 and 24 thereon operatively engaging the beveled pinion 20 and a similar pinion 25 on the end of the roll *e*. Thus when the teeth on the gear 6 run off the pinion 7 and the presser-roll *x* comes to a rest the two pairs of feed-rolls *d e* and *f g* are also arrested, and it is at this time that the shearing operation takes place, which will now be described. Outside of the gear 6 and also on the driving-shaft is another broken gear 26, which is 90 illustrated in Figs. 6 and 7 and which by meshing at the proper time with a pinion 27 on a shaft 28, supported in suitable standards 29 directly over the drive-shaft, actuates the blade 30 through the eccentric connections of the latter with the shaft 28, as shown in Fig. 6, to shear off the metal strip *m*, which has been fed thereunder by means of the feeding devices heretofore described, the knife during this shearing movement 95 passing across the edge of the stationary knife 31, all of the above-described parts being clearly shown particularly in Figs. 4 and 6.

It will be seen by referring to Fig. 7 that 100 the part of the circumference of the gear 26 which is provided with teeth is equal to that circumferential part of the gear 6 at which there are no teeth, and the two gears 6 and 26 are so located on the driving-shaft that 105 when the gear 6 during its rotation becomes inactive relative to its pinion 7 at the same moment the toothed part of the gear 26 enters in mesh with the pinion 27 to rotate the shaft 28 and actuate the steering devices in the 110 manner described, the pinion 27 making one revolution, thus carrying the knife down and back. It is thus seen that the machine is 115 entirely automatic in its operation of coating the strip of material and cutting off the same in predetermined lengths.

Beyond the shearing devices any kind of a table or chute may be provided to receive the cut lengths of the coated material.

In operation the adhesive substance with 125 which the material is coated is put into the bed *b* and by means of the burners underneath brought to a proper state of fluidity, the metal strip then being introduced between the rolls *d e*, carried under the idler- 130

roll *o*, thence through the other feed-rolls *g* and *f*. If the machine now be started, the strip will be fed between the presser-rolls *w* and *x*, and the two strips of coating material from the rolls *t* and *v* will be carried, respectively, under the presser-rolls and pressed firmly against each side of the strip of material until a certain predetermined length has passed, whereupon these rolls and the feed-rolls become stationary and the shearing device is operated to cut off the length of material thus coated, whereupon the operation is resumed.

Having thus described my invention, what I claim, and desire to secure by Letters Patent of the United States, is—

1. A coating-machine of the character described comprising a trough for the liquid adhesive, suitable feed-rolls to carry a strip of body material through the adhesive in the trough; wiper-rolls, and presser-rolls between which the strip of material is fed, and means to apply a coating strip to each side of the strip of body material prior to the passage of the latter through the presser-rolls, and a suitable mechanism to automatically cut said body-strip into predetermined lengths after its passage through the presser-rolls, said cutting means operating when the feeding-rolls are stationary.

2. In a coating-machine of the character described, a trough for the liquid adhesive, feed-rolls located at each end of the trough to carry a strip of body material through the adhesive, certain of said feed-rolls constituting wiper-rolls; presser-rolls located beyond the wiper-rolls, and means to feed a strip of coating material through the presser-rolls in contact with the opposite sides of said strip of body material, and a suitable mechanism to automatically cut said strip of material into predetermined lengths after its passage through the presser-rolls, said cutting means operating at the instant the feeding-rolls become stationary.

3. In a coating-machine of the character described, a trough for the liquid adhesive, feed-rolls located at each end of the trough to carry a strip of body material through the adhesive, certain of said feed-rolls constituting wiper-rolls; presser-rolls located beyond the wiper-rolls, and means to feed a strip of coating material through the presser-rolls in contact with the opposite sides of said strip of body material, and a suitable mechanism to automatically cut said strip of material into predetermined lengths after its passage through the presser-rolls, together with devices to arrest the movement of the feed-

rolls and presser-rolls during the cutting operation.

4. In a coating-machine of the character described, a suitable trough for the liquid adhesive, feed-rolls located at opposite ends of the trough to carry a strip of body material through the adhesive, one pair of said feed-rolls constituting wiper-rolls; presser-rolls located beyond the wiper-rolls, and a suitable driving connection between the presser-rolls and the feed-rolls, together with suitable devices to arrest the presser-roll periodically comprising a set of mutilated gears between the driving means and the feed-rolls, and shearing mechanism to cut the strip of body material while the presser-rolls are inactive, said shearing mechanism being operatively connected to said driving means.

5. A coating-machine of the character described comprising a trough for the liquid adhesive, suitable feed-rolls to carry a strip of body material through the adhesive in the trough; wiper-rolls, and presser-rolls between which the strip of body material is fed, and means to apply a coating strip to each side of the strip of body material prior to the passage of the latter through the presser-rolls; a suitable driving connection between the presser-rolls and the feed-rolls and wiper-rolls; a driving-shaft, and a broken gear mounted thereon to engage the presser-rolls; whereby the latter may be rotated intermittently; a shearing mechanism to cut the strip after its passage through the presser-rolls, and means to actuate said shearing mechanism when the presser-rolls are at rest.

6. A coating-machine of the character described comprising a trough for the liquid adhesive, suitable feed-rolls to carry a strip of body material through the adhesive in the trough; wiper-rolls, and presser-rolls between which the strip of material is fed, and means to apply a coating strip to each side of the strip of body material prior to the passage of the latter through the presser-rolls, a suitable driving connection between the presser-rolls and the feed-rolls and wiper-rolls, a driving-shaft, and a shearing mechanism to cut the strip after its passage through the presser-rolls, and two broken gears mounted on the driving-shaft one of which is operatively connected with the rolls, and the other of which is operatively connected with said shearing mechanism the one being operative while the other is at rest.

FRANK DAVIS JACOBS.
